WIND INSTRUMENTS

John de Lancie, 2015 Chestnut Ave., Ardmore, Pa., and
W Hans Moennig, Philadelphia, Pa.; said Moennig as-
signor to said De Lancie

Filed Oct. 8, 1962, Ser. No. 229,006
8 Claims. (Cl. 84—380)

This invention or discovery relates to wind instruments and is particularly useful in the class of musical instruments designated wood-winds, being especially significant to the oboe; and it will be applied as to the oboe that the invention will be herein fully disclosed in detail, by way of preferred example.

The primary object of the invention is the improvement of the relative intonation of different portions of the range of the instrument while at the same time maintaining or improving the character and quality of the tone produced by the instrument. The significance of the invention or discovery in this important respect will be more readily seen after consideration of certain basic deficiencies of wind instruments as heretofore known.

It is well known that various tones in the scale of a wind instrument tend to be off-pitch with relation to other tones, and that the player must make adjustments for this, as by alterations in air pressure, lip tension or pressure, fingering, et cetera. In certain instruments, a tone or group of tones in one portion of the range of the instrument will tend to be off-pitch with relation to a corresponding tone or group of tones in a second portion of the range intended to be an octave higher or lower; so that there is not a perfect octave relationship. This problem is especially troublesome in the oboe, particularly in connection with the pitch relation between the low-register tones from B-flat to E-flat (on the one hand) and the high-register tones from B-flat to E-flat (on the other hand). Low-register B-flat here means the B-flat below middle C, and high-register B-flat means the B-flat which should sound a perfect octave above the low B-flat.

Prior to the present invention, the difference in pitch between any one of the above-mentioned group of notes in one register (on the oboe) and the corresponding note of the specified group in the other register has regularly been greater than a perfect octave. By careful proportioning of the length and the continuously-uniform taper of the bore, throughout the area of the bore penetrated by the tone-holes (now usually twenty in number), and by various adjustments of the size, shape and location of the tone-holes, the oboe maker has been able to obtain a reasonable degree of accuracy in the pitch relationship between the various tones from B-flat to E-flat in either one of the two registers above-mentioned, but the octave relationship between those tones and the corresponding tones of the other register has been greater than a perfect octave.

Accordingly, the oboe maker has been faced with the choice of proportioning the oboe to give substantially accurate pitch to the critical group of tones (generally B-flat to E-flat) in the low register, with the result that the corresponding critical group in the high register will be too sharp; or proportioning the instrument to give substantially accurate pitch to the said group of tones in the high register, with a resulting flat intonation of the corresponding group in the lower register. Since the "first oboist" or "solo oboist" must play the critical notes in the upper register with much greater frequency than the corresponding notes in the lower register, it is almost universal for the oboe maker to so proportion the instrument as to favor the accuracy of the upper portion of the range, with the inevitable result that the playing of the lower octave (especially the critical group of notes) with accuracy of intonation has presented enormous dif-

2

ficulties to the oboist. In addition, because of this characteristic of the instrument and also because of the adjustments of embouchure, air pressure, and the like, which must accordingly be made by the player, the several notes at the lowest part of the range tend to "bubble" or oscillate in pitch, giving what is sometimes called "double-talk," which of course represents a decided impairment of the tone quality and character of the instrument. Hence the lot of the "second oboist" in a symphony orchestra (who customarily plays in the lower portions of the oboe's range) has been particularly difficult.

In accordance with the present invention or discovery, the difficulties above described are minimized or substantially obviated by a special contouring of the bore 15 of the instrument in a particular intermediate region of the length thereof. More particularly, these advantages are secured by the incorporation of an abrupt change of bore diameter at a certain point in said region and/or by the incorporation, in said region, of a bore taper angle 20 different from the angle of taper of the immediately preceding portion of the bore. It is believed that each of these two features, of itself, contributes to the ultimate result, but that the two in combination coact to produce the most accurate octave relationship throughout the 25 scale and a decided improvement in the character, quality and ease of production of the lowermost tones of the instrument.

The location of the abrupt change of bore diameter, and the character and disposition of the bore sections of 30 two different angles of taper may be described in relation to several of the areas and physical parts of the instrument. Thus, if we consider the over-all length of the instrument (from the tip of the reed of the mouthpiece to the end of the bell) the abrupt change in bore diameter, 35 according to the present invention, should be made at a location in the middle third of the length of the instrument and preferably fairly close to the mid-point of that length. If adjacent segments of the bore are respectively provided with different angles of taper, each segment having its own uniform taper, according to the present invention the juncture of those two segments is made at a location in the middle third and preferably fairly close to the mid-point of the over-all length of the instrument. When either or both the features referred to are employed, the "location" above-described may for convenience be termed the critical location or the critical point. When we consider the region of the bore of an oboe extending from the uppermost tone-hole to the lowermost 45 tone-hole (in an oboe having twenty tone-holes), the best practice of the invention is to so locate both the abrupt change of bore diameter and the meeting of said two different tapers that ten tone-holes are located above the critical point and ten tone-holes below it.

In different oboes, it may be necessary to have some 50 variation in the location of the point of abrupt change in bore diameter and/or location of change in angle of bore taper. This possible variation may best be described with reference to the three parts or "joints" of which the oboe usually consists. Taking these three parts as the 55 length of the instrument proper (omitting the mouthpiece or reed), the critical point hereinabove referred to will generally be found to be at a point between one-third and one-half the length of the bore of the instrument, measured from the commencement of the tapered bore, immediately subjacent the mouthpiece.

In the average oboe of today, excellent results in accordance with the present invention may be obtained by arbitrarily placing the critical point at or fairly close to the juncture of the "upper" joint and the "lower" 60 joint as hereinafter defined.

Still more specifically, as to the oboe, the practice of the present invention or discovery involves an abrupt

increase in bore diameter at the critical point, while at the same time the angle of taper of the bore from the critical point downwards is correspondingly reduced as compared with the angle of taper of the bore thereabove, in order to obtain substantial accuracy of the entire scale of the instrument.

How the invention is put into practice in an oboe, and how the objects and advantages hereinabove set forth are obtained, will appear more fully from the detailed description of a typical embodiment of the invention as hereinafter given, when taken together with the accompanying drawing. In the drawing:

FIGURE 1 is a longitudinal sectional view of an oboe, drawn to less than half scale, with the mouthpiece inserted in the upper end (the reed portion of the mouthpiece being indicated in phantom outline, with a portion broken out), this view showing the relative locations and relative sizes of the twenty tone-holes, also showing a number of the valves and a fragmentary indication of valve operating mechanism; the instrument as illustrated incorporating the present invention or discovery in the best embodiment at present known;

FIGURE 2 is an enlarged fragmentary section (which, in the original patent application drawing, is on a scale twice actual size) showing the separable connection between the upper segment or "upper joint" (as it is commonly termed) of the instrument and the next adjacent segment (commonly termed "lower joint");

FIGURE 3 is a sectional view on the line 3—3 of FIGURE 2; and

FIGURE 4 is a broken-away exploded longitudinal sectional view showing portions of the three cooperating segments of the oboe, generally termed "upper joint," "lower joint," and "bell joint," illustrating clearly the separable connections or couplings between said joints (this view being drawn to actual size, on the original patent application drawing).

Before proceeding with the features which are novel with the present invention or discovery, as applied to the oboe, we will briefly describe certain characteristics of oboes in general.

Although in oboes of different models, periods, or makes, there would be differences from one instrument to another, the latter differences, i.e. differences between one oboe and another in current use, would be negligible, so far as concerns over-all length, general shape and proportions, diameter of bore at the point where the mouthpiece is seated, diameter of bore where the bell is coupled to the lower joint, outlet diameter of bell, etc. Prior to the present invention or discovery, it has been customary to make the oboe bore of a continuous uniform taper, from the point where the mouthpiece is seated down to the lower end of the lower joint, and usually down to a location part way down into the bell joint; and for the last hundred years or more, it has been customary to employ fairly standard bore diameters at certain locations in this truncated conical bore, i.e. about 4 millimeters diameter at the upper end of said uniformly tapered bore and about 16½ millimeters at the lower end thereof. In such instruments, the standard bore dimension at the lower end of the upper joint and at the mating upper end of the lower joint is about 10 millimeters.

As above indicated, the uniformly-tapered portion of the bore customarily extends partway down into the upper end of the bell joint, so that the initial taper therein (down to a point about 17 or 18 millimeters below the seating point of the lower joint within the bell joint) is a direct continuation of the taper of the bore above it. However, from that point downwards, the bore of the bell joint normally flares substantially, as shown at F, so that at the extreme lower end of the instrument the diameter of the opening may be 35 or more millimeters.

In the drawings, the upper joint of an oboe is shown at U, the lower joint at L and the bell joint at B. (Some-

times the section or joint L is termed the "middle joint" and the bell joint B termed the "lower joint"—but to avoid confusion we will herein regularly apply the term "lower joint" L only to the intermediate section of the instrument, and will regularly designate the bottom section as the "bell joint" B.) What is sometimes termed the mouthpiece and sometimes termed the reed is shown at the upper end at M. This usually comprises a tapered metal tube or ferrule 5 (also termed "staple") having a reed 6 secured thereto, said tube being surrounded at its lower end by a cork facing 7 which forms an airtight fit within the metal sleeve 8 inside the shouldered upper end 9 of the instrument proper (see FIG. 4). The reed, as shown, is partly broken away, so that it appears to be shortened.

The upper joint U has a series of tone-holes (10 in number) of varying sizes and variously located, these being indicated at 11. These holes are opened and closed by the valves or keys 12, normally actuated by the valve operating mechanism, small fragments of which are shown at 13.

Similar tone-holes of various sizes and varying locations communicate with the bore of the lower section L, as indicated at 11', there being typically nine of them in the lower joint L. The lowest tone-hole 11" is disposed in the upper end of the bell joint B. Valves 12 for these tone-holes are of course also provided.

As best seen in FIGURES 2 and 4, the coupling or connection between the upper joint U and the lower joint L comprises a socket portion S, provided at the upper end of the lower joint L, and a tenon portion T provided at the lower end of the upper joint U. Metallic sleeves 14, 14' and 15 may be supplied at this connection, in accordance with standard practice, together with a cork sleeve 16 to make an air-tight seal.

A similar mode of connection may be employed between the lower joint L and the bell joint B, as indicated by the socket S2 and the tenon T2. Metallic sleeves and a cork sleeve may also be employed at that connection—the same being unnumbered in the drawings, but being similar to the parts 14, 14' and 15, except as to details of size and shape.

Certain dimensions, typical of oboes in use today (though subject to some variation) are as follows:

From point a (at the tip of the reed) to point b (where the instrument proper commences) is about 79 millimeters. (This distance appears less than in proportion to other distances shown, because the reed 6 has been broken away, as indicated.) From point b to point c (where the reed or mouthpiece seats on a shoulder inside the instrument) is about 19 millimeters. From point c to point d (at the shoulder or base of the tenon T) is about 213 millimeters. From point d to point e (the seating surface of the inturned flange of the metal sleeve 15) is about 18 millimeters. From point e to point f (the base of tenon T2) is about 221 millimeters. From point f to point g (the seating surface of the flange at the bottom of tenon T2) is about 17 millimeters. From point g to point h (where the flare within the bell b commences) is about 18 millimeters. From point h, where flare F begins, to point i (the lowermost end of the bell) is about 91 millimeters. With the parts of the instrument all assembled, the overall length from point a to point i is thus about 676 millimeters.

In the usual oboe, the bore, through a distance from point or location c to point or location h is of one continuous uniform taper. In other words, it is a truncated continuous cone, in the ordinary oboe. This conical bore (of continuous taper in the ordinary instrument) measures approximately 487 millimeters, from c to h. As to diameter, said conical bore normally measures about 4 millimeters at point c, about 10 millimeters at point e, about 16 millimeters at point g, and about 16.5 millimeters at point h. Point e, where the lower end of the tenon of the upper section U seats in the socket of the

lower section L, is at a location not quite halfway down from point c to point h, but it may be taken roughly as the mid-point of the standard conical bore, and it will be noted that ten of the tone-holes are above point e and ten of them (inclusive of the hole 11" in the bell joint) are below the point e.

Considering the instrument as a whole (from point a to point i) the point e is in the middle third of the length, though not exactly at the mid-point. When one considers the bore only, of the instrument proper, that is, the total bore from the base of the reed to the bottom of the bell (i.e. from point c to point i), it will be found that the coupling or junction point e, in nearly all oboes today, lies between one-third and one-half of the distance down from the upper end of said total bore. This is a factor which is put to practical use in connection with the present invention or discovery, as applied to the oboe, as will hereinafter appear.

In applying the invention to instruments other than the oboe (e.g. the English horn or the bassoon) the shapes, sizes, proportions, and relative disposition and arrangement, of the parts would of course be quite different from those for the oboe; but the oboe will serve very well as the typical example for the application of the invention, especially in view of the extremely difficult problems in the matter of the octave relationship and the quality of low tones, as discussed in the initial part of this specification.

In applying the invention or discovery to the oboe, according to the best embodiment at present known, we introduce an abrupt change in bore diameter, at a point (hereinbefore referred to as the "critical point") which by experiment has been found to be, for satisfactory results, between about one-third and one-half of the distance from the small end toward the large end of the total bore of the instrument (as measured from the seating shoulder for the mouthpiece down to the outlet end of the bell), which places it within the middle third of the instrument (as measured from the tip of the reed to the outlet end of the bell). The preferred location of said abrupt change, for the best results in today's oboe of otherwise average dimensions, is found to be just slightly above the mid-point of said overall length—approximately 5 to 15 millimeters above said mid-point. At or near the same location, the second taper angle is introduced, and this is extended downwardly through approximately the next 30 to 40% of the over-all length of the instrument, so that the said second taper extends at least down to the lower end of the lower joint, or, for best results, down to a point about 18 millimeters below the bottom of the shoulder or socket of the bell joint.

The abrupt change in bore, for the average oboe of today, should be an increase in diameter amounting to somewhere between 3½% and 8% of the normal diameter at the critical point. For example, when the normal bore diameter at the lowermost end of the upper joint U is 10 millimeters, the bore immediately below that (i.e., the bore of lower joint L, commencing at location e) is increased to 10½ millimeters diameter. This 5% increase, at the point indicated, is sufficient for the purposes of the present invention, especially if the taper angle of the bore from point e down to point h—or at least down to point g—is made smaller than the taper angle of the bore from point c to point e. This may be done by employing the normal bore dimension at h (typically 16.5 mm.) and boaring out the instrument from e to h at such continuous taper angle as will produce a bore diameter of 10.5 mm. at point e and 16.5 mm. at point h.

The resulting shouldered effect in the bore of the instrument is clearly seen at SH in the cross-sectional view of FIGURE 3, which is a view looking up into the bore, from a point at the line 3—3 of FIGURE 2, i.e. from immediately below the location e of FIGURE 1. In FIGURE 3, the conical bore C of upper joint U is clearly seen, and its normal dimensions of 4 millimeters at the

uppermost end and 10 millimeters at its lower end are indicated. The conical bore C', extending from location e to location h, in FIG. 1, is indicated in FIG. 3 by full-line and dotted-line circles, the one marked 10.5 being the 10½ mm. diameter of the upper end of said bore (corresponding to location e in FIGURE 1) and the dotted circle, marked 16.5, representing the 16½ mm. diameter (corresponding to location h in the bell joint B). Typical bore dimensions of an oboe embodying the present invention are also indicated at the right of FIG. 4.

Alternatively, the bore from g to h, in the bell joint B may remain normal (typically 16 mm. at point g and 16½ mm. at point h), in which event the joint L is bored at such a taper that the bore diameter is 10½ mm. at point e and 16 mm. at point g. By following this latter procedure, not only is the upper joint U of the instrument made to heretofore normal contours and bore dimensions, but so also is the entire bell joint B, i.e. with its usual conical bore from g to h and its usual flare F from h to i.

Accordingly, it is possible to convert an existing oboe to one largely conforming with our invention or discovery; by leaving the upper joint U and the bell joint B in their original condition, and re-boring only the lower joint L, to a new angle of taper, from location e down to location g, in such a way that the bore is made larger at said upper end while retaining its originally existing diameter at the lower end, thereby at the same time producing the desired abrupt increase in bore diameter at the point of coupling of the upper joint with the lower joint.

In putting the invention into practice, it is not necessary to make any change in the materials of which the instrument is made. If the oboe is made of the usual close-grained hardwoods, of a character to produce a pleasing tone quality of the desired degree of mellowness, the incorporation therein of the novel bore characteristics of the present invention or discovery will maintain the desirable tone quality, and in general will actually enhance the same in the lower register, while at the same time reducing the tendency to distortion or "bubbling" of the lowermost tones, rendering much truer the octave relationship between the critical group of tones in the high register and the corresponding critical group of tones in the low register, and finally, as a consequence of those advantages, rendering the instrument easier to play.

We claim:

1. A wind instrument having a tapered bore throughout most of its length, and having a plurality of controllable tone-holes disposed therealong including a lowermost series of tone-holes for the lowest octave of which the instrument is capable, the bore diameter progressively changing and having its minimum diameter adjacent the mouthpiece end of the instrument and its maximum diameter adjacent the other end, and said bore further having an abrupt change of bore diameter at a location near the upper end of said lowermost series of tone-holes.

2. A wind instrument having a tapered bore throughout most of its length, and having a plurality of controllable tone-holes disposed therealong including a lowermost series of tone-holes for the lowest octave of which the instrument is capable, the bore diameter progressively changing and having its minimum diameter adjacent the mouthpiece end of the instrument and its maximum diameter adjacent the other end, and said bore further having an abrupt change of bore diameter at a location near the upper end of said lowermost series of tone-holes; the instrument comprising separable sections coupled together adjacent said location where the abrupt change of bore diameter occurs.

3. A wind instrument having a tapered bore throughout most of its length, and having a plurality of controllable tone-holes disposed therealong including a lowermost series of tone-holes for the lowest octave of which the instrument is capable, two adjacent segments of said bore having different taper angles, one of said segments ex-

tending throughout most of the distance occupied by said lowermost series of tone-holes being of one uniform taper angle, and the immediately superjacent segment being of another uniform taper angle.

4. A wind instrument having a tapered bore throughout most of its length, and having a plurality of controllable tone-holes disposed therealong including a lowermost series of tone-holes for the lowest octave of which the instrument is capable, two adjacent segments of said bore having different taper angles, one of said segments extending throughout most of the distance occupied by said lowermost series of tone-holes being of one uniform taper angle, and the immediately superjacent segment being of another uniform taper angle; the instrument comprising separable sections coupled together adjacent to the juncture of said two differently-tapered segments of the bore.

5. A wind instrument having a tapered bore throughout most of its length, said bore having different angles of taper in different segments of its length, and having a plurality of controllable tone-holes disposed therealong, including a lowermost series for the lowest octave of which the instrument is capable, and said bore further having a shoulder adjacent the juncture of the different tapers, and said shoulder being near that location in the length of the bore which corresponds to an octave of pitch above the lowermost pitch of the instrument.

6. A wind instrument having a generally tapered bore and having a mouthpiece at one end and a bell at the opposite end, said instrument having a uniform taper from adjacent the mouthpiece to a location about the midpoint of the total length of the bore and at said location having an abrupt change of bore diameter, and said bore

having a uniform taper from said location to the bell of the instrument.

7. A wind instrument of oboe type, having an upper joint and a lower joint, separably coupled, each joint having a bore of substantially uniform taper, a series of tone-holes approximately evenly divided between said two joints, the minimum effective bore diameter at the upper end of the lower joint being larger than the maximum effective bore diameter at the lower end of the upper joint, and the ratio of said two specified bore diameters being approximately 10.5 to 10.

8. A wind instrument of oboe type, having an upper joint and a lower joint, separably coupled, each joint having a bore of substantially uniform taper, a series of tone-holes approximately evenly divided between said two joints, the minimum effective bore diameter at the upper end of the lower joint being about 3½% to 8% larger than the maximum effective bore diameter at the lower end of the upper joint, and the taper angle of the bore of the lower joint being less than the taper angle of the bore of the upper joint.
